UNITED STATES PATENT OFFICE.

EDWARD D. MORRIS, OF CHICAGO, ILLINOIS.

DESIGN FOR A TILE-DISPLAY STAND.

SPECIFICATION forming part of Design No. 16,998, dated November 23, 1886.

Application filed June 3, 1886. Serial No. 294,098. Term of patent 14 years.

To all whom it may concern:

Be it known that I, EDWARD D. MORRIS, a subject of the Queen of Great Britain, residing at Chicago, in the county of Cook and State 5 of Illinois, have invented and produced a new and original Design for a Tile-Display Stand; and I hereby declare the following to be a full, clear, and exact description of the same.

My invention relates to a new and original 10 design for a display-stand; and it consists in a base rectangular in outline, having side ledges, and legs located at the corners of the base, the whole presenting continuous unbroken lines, as if made out of a single piece of mate- 15 rial, and a tile superimposed upon the whole.

In the drawings, Figure 1 represents a plan view of my invention, and Fig. 2 a central vertical section of the same.

A is the stand, having the side ledges, *r*, and base *q*, and plain ornamental legs *p*, located at 20 the corners of the base, the whole presenting continuous unbroken lines. The tile *B*, of any ornamental design, is superimposed upon the base *q*, between the ledges *r* of the stand.

What I claim as new is—

The design for a tile-display stand herein shown and described, comprising the base *q*, rectangular in outline, having side ledges, *r*, and legs *p*, located at the corners of the base, the whole presenting continuous unbroken 30 lines, and a tile, *B*, superimposed upon the base.

EDWARD D. MORRIS.

In presence of—

J. W. DYRENFORTH,
HENRY HUDSON.
